ARNEL WEEKS, OF SYRACUSE, NEW YORK.

Letters Patent No. 79,423, dated June 30, 1868.

IMPROVEMENT IN MACHINES FOR MAKING CIGARS.

The Schedule referred to in these Letters Patent and making part of the same.

TO ALL WHOM IT MAY CONCERN:

Be it known that I, ARNEL WEEKS, of Syracuse, in the county of Onondaga, and State of New York, have invented certain new and useful Improvements in Machines for Making Cigars, of which the following is a full, clear, and exact description, reference being had to the accompanying drawings, which make part of this specification, and in which—

Figure 1 represents a plan or top view of a machine to which my improvements are applied.

Figure 2 represents a vertical transverse section through the same at the line $z z$ of fig. 1; and

Figure 3, a plan or top view of a portion of the machine, showing the lower rolls.

My invention relates to that class of machines in which the cigars are formed and wrapped by means of revolving rollers; and the objects of my improvements are, first, to apply the binders and wrappers by successive operations of the same machine; and, secondly, to make two cigars at one operation; to which ends the invention herein claimed consists in certain novel devices and combinations of mechanism, hereinafter more fully described, for attaining these results.

In order to carry out the objects of my invention, I mount the mechanism in a stout frame, consisting, in this instance, of two end-pieces, A, connected by proper cross-bars, and having a table, B, in front of the rollers.

The cigar is formed between revolving rollers, arranged lengthwise of the frame, parallel to each other, and of the form shown in the drawings, that is, swelled in the middle, and tapering towards each end, by which means two cigars can be formed at once, as hereinafter explained. I prefer to make these rollers of wood, and to cover them with India rubber, gutta percha, or leather.

The main or driving-roller C is arranged to revolve close to the inner edge of the table, and may be driven by a crank, e, or by a pulley, e', on its axis outside the frame, in any proper well-known way.

Revolving heading-dies, D, turn in proper bearings in the end-pieces A, and are driven by cords or bands, d, encircling pulleys d on both ends of the roller C, and pulleys d' on the dies. By driving these dies from the outer side of the frame, the space between the end-pieces, above the table B, is left unobstructed. The dies are cup-shaped internally, in order to round off the end of the cigar when placed within them.

A second roller, E, is arranged behind the first one, C, and driven by a band, e, from the main roller.

A third roller, F, fig. 2, is arranged below and between the other two above mentioned, and is driven by the same band, e, that drives the second roller E. The three rollers above mentioned are all mounted in rigid bearings in the frame, so as not to yield to the pressure when wrapping the cigar.

A fourth or compressing-roller, G, is mounted in bearings in a frame, H, pivoted to vibrate vertically around an axis or shaft, I, at the back of the machine. This roller revolves by frictional contact with the rolls merely, and is arranged so as to lie above and between the first and second rollers.

All the rollers have rims, f, on their ends, which revolve in contact with each other. The central portions of the rollers are of smaller diameters than these rims, so as to leave a space between them, as shown in fig. 2. The space thus left is filled at each end by a fixed head-block, J, figs. 2 and 3, which prevents the filling from spreading endwise.

The swing-frame H is vibrated by means of a treadle, K, rocking on a pivot, k, on the periphery of a rock-shaft, L, and connected, by a link-rod, M, with a cross-bar, h, attached to the swing-frame at a point between its axis of oscillation, I, and the roller G.

The fulcrum-pin k works in a slot in the treadle, so as to play slightly backwards and forwards. The shaft L also has a rocking motion on its axis, and the treadle and link-rod M are connected by a joint, which allows them to play freely vertically. By this means the swing-frame H and roller G cannot only be raised or lowered, but can be thrown back into the position shown by the red lines in fig. 2; and held there.

I prefer to use belts or cords instead of gearing, as the latter is noisy, and may be broken by any sudden obstruction of its motion, whereas belts are run quietly, and slip when an obstruction stops the machinery.

The operation of the machine is as follows: The operator, standing in front of the table B, makes up his

filling long enough to form two cigars of the size to be made, places it between the fixed rollers, lowers the compressing-roller upon it, places the edge of the binder between the rollers C G, and starts the machine. The rotation of the rollers compresses and shapes the filling and simultaneously applies the binding. When the binding has been applied, the operator, without stopping the machine, inserts the edge of the wrapper, which is applied in the same manner as the binder, by the continued rotation of the rollers. When the wrappers have been applied, and sufficiently smoothed, the compressing-roller G is lifted into the position shown in red lines in fig. 2, by means of the treadle, and the cigar removed. The operator holding the cigar in the middle, applies first one end and then the other to the revolving heading-dies, by which the ends are finished. The cigar is then cut in two in the middle, and is ready for market.

It will thus be seen that I am enabled by my invention to apply the wrapping and binding by one continuous operation of the same machine, and to make two cigars at once by the use of very simple mechanism.

I am aware that the use of treadles, movable rollers, and heading-dies is not new, and do not, therefore, broadly claim any of these devices; but I am not aware of any machine which combines these devices in the manner claimed by me.

Having thus fully described the construction and operation of my improved machine, what I claim therein as new, and desire to secure by Letters Patent, is—

1. The combination, in a cigar-machine, of the three peculiarly-formed elastic rollers C E F, mounted in rigid bearings, and driven by a band, with the similarly-formed elastic compressing-roller G mounted in the vertically-vibrating frame H, and rotated by frictional contact merely with the other rollers, whereby I am enabled to apply both the binders and wrappers to two cigars simultaneously by one continuous operation of the same machine, as set forth.

2. The combination, substantially as set forth, with the driving-roller C, of the heading-dies D, arranged at a distance apart greater than the length of the two finished cigars, whereby one end of each cigar may be finished by its respective die.

3. The combination of the peculiarly-shaped rollers, the flanges f, and the interposed fixed head-blocks J, these parts being arranged, as set forth, for joint operation.

In testimony whereof, I have hereunto subscribed my name.

ARNEL WEEKS.
